UNITED STATES PATENT OFFICE.

WILLIAM T. WARDALL, OF NEAR MANLY JUNCTION, IOWA.

DOUBLE CUTTER-BAR.

SPECIFICATION forming part of Letters Patent No. 375,237, dated December 20, 1887.

Application filed June 21, 1887. Serial No. 242,006. (No model.)

To all whom it may concern:

Be it known that I, WILLIAM T. WARDALL, residing near Manly Junction, in the county of Worth and State of Iowa, have invented a new and Improved Double Cutter-Bar, of which the following is a full, clear, and exact description.

This invention relates to a novel form of double cutter-bar for the finger-bars of reapers and mowers, the object of the invention being to provide a double cutter-bar which will not clog, and one wherein the parts are so constructed that the cutters may be adjusted so as to operate in the most effective position.

Reference is to be had to the accompanying drawings, forming a part of this specification, in which similar figures of reference indicate corresponding parts in all the views.

Figure 1 is a plan view of my improved form 20 of double cutter-bar. Fig. 2 is a sectional view taken on line $x-x$ of Fig. 3. Fig. 3 is a cross-sectional view taken on line $y-y$ of Fig. 1, the outer guard being broken away; and Fig. 4 is a detail view illustrating the connection between the cutters and one of the cutter-bars.

In constructing such a cutting apparatus as the one illustrated in the drawings above referred to I provide two cutter-bars, 10 and 11, to each of which cutter-bars there are connected a number of cutters, 12, each of said cutters being formed with slots 2, through which there are passed set-screws 3, by means of which the cutters are connected to the cutter-bars, the arrangement being such that as the inclined edges of the cutters are worn away by use and by being sharpened the cutters may be moved forward, so that their cutting-edges will always operate in the same relative position. These cutter-bars are placed face to face, and are mounted to slide in recesses that are formed in finger-bars 13, the sections of said finger-bars being held together by tap-bolts 14, which pass through elongated apertures 15, that are formed in a spacing-strip, 16, that is placed between the two sections at the rear of the cutter-bars, the arrangement being such that by moving the spacing-strip 16 forward the cutting-edges of the cutters 12 may be kept in the required position.

To the finger-bar 13 there are connected

guard-fingers 17, the width of which is equal to the width of the cutters 12, and these guard-fingers are so mounted that the space between them is equal to the width of the guard-fingers, 55 and consequently to the width of the cutters. The guard-fingers 17 are held to the finger-bar 13 by bolts 5, which pass through the rearward-extending portions 18 of the guard-fingers and engage with the finger-bar, as indicated in Fig. 3. The inner or main shoe, 20, is a little more than double the width of the cutters, while the outer shoe or divider, 21, is preferably one and a half times as wide as the cutters, and this divider 21 is so shaped that it 65 will gather the grass to the sickle-bars.

The track-clearer, which is shown at 50, is mounted in the rear of the divider 21, the shank of this track-clearer being formed with a transverse aperture, 3, and a vertical aperture, 4, 70 these apertures being somewhat elongated. Through the aperture 3 there is passed a supporting-rod, 5^a, while through the aperture 4 there is passed a vertical rod, 6, springs 7 being arranged above and below the shank of the 75 track-clearer and about the rod 6, and other springs, 8, (see Fig. 2,) are arranged upon each side of the shank of the track-clearer and about the rod 5, the arrangement being such that while the divider is yieldingly held in position it may 80 be adjusted by means of the nuts 9, in which the ends of the rods 5^a and 6 ride, said nuts being mounted in proper sockets that are formed in the guard 21.

In operation the usual reciprocating motion 85 is imparted to the two cutter-bars by any of the ordinary cutter-bar-operating mechanisms in use.

Having thus fully described my invention, I claim as new and desire to secure by Letters 90 Patent—

1. The combination, with two cutter-bars and their cutters, of a spacing-strip arranged between the sections of the finger-bar and formed with slots through which the connecting-bolts pass, substantially as described.

2. The combination, with a finger-bar and a divider, of the clearer having its forward end pivoted and supported upon a horizontal rod to move from side to side and pivoted upon 100 and guided by a vertical rod to slide up and down, and springs, two disposed upon each

rod, one above and one below the clearer upon the vertical rod and one upon each side of the clearer upon the horizontal rod, substantially as set forth.

5 3. The combination, with a finger-bar and a divider, of the clearer having its forward end pivoted and supported upon a horizontal rod to move from side to side and pivoted upon and guided by a vertical rod to slide up and down, springs, two disposed upon each rod,

one above and one below the clearer upon the vertical rod and one upon each side of the clearer upon the horizontal rod, and the adjusting-screws working in the divider and bearing against the ends of the said horizontal and vertical rods, substantially as set forth. 15

WILLIAM T. WARDALL.
